CARTRIDGE CASE FOR FIREARMS

Adolf Victor Schillström, Eskilstuna, Sweden

Application April 1, 1939, Serial No. 265,424
In Sweden April 28, 1938

3 Claims. (Cl. 42—50)

This invention relates to cartridge cases for firearms and more particularly to a cartridge case which is provided with spring pressed feeder blocks one on each side of a dividing wall, which blocks feed the cartridges in double rows towards a constricted mouth of the case through which they are delivered one at a time.

In a cartridge case embodying the invention, each cartridge feeder block is of a form to support two cartridges upon different levels and to move upwardly in the magazine in which it has movement. The walls of the case and the dividing wall, forming two parallel magazines, guide the feeder blocks in this movement of the blocks and the cartridges. The side walls of the case converge towards each other from a point below the top of the dividing wall and are spaced apart to form an open mouth for the delivery of the cartridge to the firearm. Each converging portion has a pocket formed therein for the reception of a part of the feeder block, said pockets being closed at the top to limit feeding movement of the block and being of different lengths to permit greater movement of one of the blocks as compared with the other. This permits the successive delivery of the last few cartridges from both magazines in a single line of cartridges.

The cartridge feeder which is first stopped in its feeding movement, is provided with a forked top, one arm of which is shorter than the other, so that when this cartridge feeder block is in its uppermost position the longer arm forms a continuation of the dividing wall forming the two magazines. The cartridge nearest the mouth of the cartridge case is kept in place by means of inwardly bent lips at one side of the discharge opening or mouth of the case, and is fed in the usual manner into the charge chamber of the firearm.

40 The upper part of the case is so formed that the four rows of cartridges in the two magazines successively merge into one row at the mouth.

Referring to the drawing, Figs. 1 and 2 show vertical sections of a cartridge case made in accordance with the invention and Fig. 3 is a section at right angles to the sections shown in Figs. 1 and 2. In Figs. 1 and 3, a large number of cartridges are shown in the case, while in Fig. 2 only three cartridges are shown.

50 The case 1 has a dividing wall 2, which divides the case into two similar parallel magazines, terminating below the mouth or outlet of the case. In each magazine a moveable cartridge feeder block 3 is slidably mounted or 4, on which the spring 10 acts to move the block and the two

staggered rows of cartridges supported thereby towards the mouth or discharge opening of the case. Each feeder block is provided with a forked top having a long arm 11 or 12 positioned adjacent the dividing wall 2, and a short arm 5 or 6 adjacent a side wall of the case. The end walls of the case, as shown in Fig. 3, are parallel throughout, but the side walls converge adjacent the upper part of the case, and are spaced apart to form a mouth or discharge opening. The dividing wall 10 5 2 terminates below the top of the case and the mouth or discharge opening, but extends above the point of initial convergence of the side walls. Below the converging side walls of the case, two rows of cartridges are supported by the feeder 16 block in each magazine, the cartridges in one row being staggered in relation to those in the other row. Between this point and the top of the wall 2, only one row of cartridges is in each magazine, while above the top of said wall there is but a 20 single row of cartridges.

Each converging side wall has a pocket 8 or 9 formed outwardly thereof, of a capacity to receive one fork 5 or 6 of the feeder block, but not wide enough to permit a cartridge to enter same, 25 thus compelling each cartridge to follow the wall (see Fig. 1). One of these pockets, as 9, is shorter than and terminates below the other pocket, as 8. The pocket 8 extends to closely adjacent the mouth or discharge opening of the case. 30

By the foregoing construction, one of the feeder blocks has its upward movement arrested when the last cartridge in the magazine has passed the top of the wall 2, while the feeder block in the other magazine is permitted to pass above the 35 said wall until all of the cartridges in both magazines have been drawn to a position where the last one may be fed into the barrel of the firearm, or with the long arm of the forked end projecting through the mouth or discharge opening. The 40 long arm of one of the feeder blocks, as 3, is bevelled, so that with tilting movement of this block as a result of the engagement of the short arm 5 with the closed end of the pocket 7, the long arm will form a continuation of the wall 2 and 45 offer no obstruction to movement of cartridges by the other feeder block 4. Both pockets 7 and 8 have closed tops, and the upper portions thereof are so inclined as to be substantially parallel with the converging side walls of the case. 50

In operation, the action of the device is substantially as follows:

The two parallel magazines formed by the side walls of the case and the partition or dividing wall 2 are each filled with cartridges, those in one 55

row being staggered in relation to those in the other row by reason of the difference in the lengths of the two arms of the forked top of the feeder block. Above the top of the wall 2 there 5 is a single row of cartridges.

- Both springs 10 are under compression. As a cartridge is removed by the mechanism in the breech of the gun barrel, one of the feeder blocks will first be raised by its spring and thus advance 10 both rows of cartridges resting thereon toward the mouth or outlet. With the movement of the next cartridge, the other feeder block will be similarly actuated. As the outer cartridge in either 15 magazine engages the converging side wall above that magazine, the cartridge of the adjacent row will be forced upwardly in advance of that cartridge, as shown in Fig. 1, so as to form a single row of cartridges within the constricted portion adjacent the mouth or discharge opening above 20 each magazine. As the space between the converging walls narrows, the same action will occur above the wall 2 so as to form a single row of cartridges substantially centrally of the case below the mouth or discharge opening.
- 25 With the progressive removal of cartridges from the case, the feeder blocks reach the converging side walls, the short arm 5 of the block 3 entering the pocket 1 and the short arm 6 of the block 4 entering the pocket 8, thus permitting continued 30 upward movement of both blocks. As the short arm 5 of the block 3 approaches the closed top of the pocket 1, this block will be tilted, as shown in Fig. 2, bringing the inner end of the long arm thereof so that the portion 9 will come into 35 alignment with the medial line of the wall 2. The top of this wall is reduced to a knife edge, as shown, to permit this movement.

When the arm 5 engages the top of the pocket 1, the last cartridge in that magazine will have 40 passed the top of the wall 2, and since at substantially the same time the long arm of the feeder block 4 will have reached the top of the wall, there will be but a single row of cartridges still in staggered relation to each other (see Fig. 45 2). The length of the pocket 8 permits the cartridges of this single row to be fed through the mouth by continued movement of the feeder block 4 by reason of the elongation of the pocket 8.

Having described the invention, what I claim 50 as new and desire to have protected by Letters Patent, is:

1. A cartridge case for firearms embodying therein a case proper having converging side walls toward the top thereof and a discharge opening 55 at the top of said walls, a wall below said converging side walls forming two magazines, each adapted to receive two rows of cartridges, a feeder

block in each magazine, a spring acting on each feeder block, means upon each block whereby the two rows of cartridges will be maintained in staggered relation to each other, co-operating means carried by one of said converging side walls and 5 by the block in the adjacent magazine for limiting movement of the block when it is adjacent the top of said dividing wall, and co-operating means carried by the other converging side wall and by the block in the adjacent magazine for 10 permitting said block to pass the dividing wall and said first named block.

2. A cartridge case for firearms embodying therein a case proper having converging side walls toward the top thereof and a discharge opening 15 at the top of said walls, a wall below said converging side walls forming two magazines, each adapted to receive two rows of cartridges, a feeder block having a forked top, one of the arms of which is longer than the other, in each magazine, 20 a spring acting on each feeder block, means upon each block whereby the two rows of cartridges will be maintained in staggered relation to each other, and an outwardly formed pocket in each converging side wall, one of said pockets terminating adjacent the top of said wall and the other terminating adjacent the discharge opening of the case, said pockets respectively being adapted to receive the shorter arm of each feeder block, whereby upward movement of one of said blocks is limited when the long arm thereof is adjacent said wall, and the other block is permitted to have movement past said first named block.

3. A cartridge case for firearms embodying therein a case proper having converging side walls toward the top thereof and a discharge opening 35 at the top of said walls, a wall below said converging side walls forming two magazines, each adapted to receive two rows of cartridges, a feeder block having a forked top, one of the arms of which is longer than the other, in each magazine, a spring acting on each feeder block, means upon each block whereby the two rows of cartridges will be maintained in staggered relation to each other, and an outwardly formed pocket in each 40 converging side wall, one of said pockets terminating adjacent the top of said wall and the other terminating adjacent the discharge opening of the case, said pockets respectively being adapted to receive the shorter arm of each feeder block, whereby upward movement of one of said blocks is limited when the long arm thereof is adjacent said wall, and the other block is permitted to have movement past said first named block, the long arm of said first named block being bevelled to 45 permit said other block to pass.

ADOLF VICTOR SCHILLSTRÖM.
